UNITED STATES PATENT OFFICE

LOFTUS B. CUDDY, OF CLEVELAND, OHIO

OIL-CRACKING STILL

Application filed July 2, 1918. Serial No. 243,030.

Figure 1 is a side elevation of a still embodying my invention;

Figure 2 is a vertical section of the same partly broken away;

Figure 3 is a transverse section on the line III—III of Figure 2; and

Figure 4 is a detail sectional view of a portion of the still.

My invention has relation to stills for cracking oil, and more particularly to that class of stills in which the cracking operation is a continuous one, the oil to be cracked being pumped into the still as the cracking proceeds.

During the cracking process, carbon freed from the oil collects on the sides of the still, and to prevent clogging of the still, must be continuously removed. The present invention has more particular relation to means of novel character for effecting such carbon removal.

The present application is a continuation of my pending application Serial No. 114,384, filed August 11, 1916, as to all subject matter common thereto.

Referring to the accompanying drawing, in which I have illustrated a preferred embodiment of my invention, and which will now be described, the numeral 2 designates a vertical still, preferably consisting of a cylindrical body with a convex head 3, welded or otherwise secured to its upper portion, as indicated at 4, and a bottom 5 of inverted cone-shape and having a central carbon discharge opening 6. This opening may be connected to any suitable carbon receiver (not shown) from which the collected carbon may be discharged from time to time.

The still is designed to be placed on a furnace such, for instance, as that shown in my application above referred to, but which forms no part of the present invention.

In accordance with my invention, I provide the still with a central vertically rotating shaft 7, having a bottom step bearing at 8, within the still, and its upper portion extending upwardly through the top of the still and through a stuffing box 9, its upper end being provided with suitable rotating means,

such as the worm wheel 10, which is engaged by a driving worm 11.

Secured to the shaft 7 at intervals within the still, one above the other, are bracket arms 12. To the outer end of each of these arms is pivoted a lever arm 13, to the free end of which is fixed a cutting or scraping blade 14, which is adapted to rotate in close proximity to the inner circumference of the wall still body. These knives or blades are yieldingly held against the inner wall of the still body by any suitable means, such as the weights 15, illustrated. In the arrangement shown, a weighted lever 16, carrying one of the weights 15, adjustably mounted thereon, is pivoted at 17, to the bent end portion 18 of each arm 12. Each of the levers 16 has a short arm or heel portion 19, which presses outwardly against the adjacent lever arm 13. The adjacent arms 12 are preferably set at different angles, and the knives or blades are so arranged that their paths will overlap sufficiently to enable them to act upon substantially the entire inner surface of the body of the still.

I also preferably provide the cone-shaped bottom 5 with an inclined scraper blade 21, shown as carried by the arm 22, fixed to the central shaft 7, and which is adapted to keep this portion of the still free of carbon and force the carbon removed by the weighted knives or blades out through the discharge 6.

The shaft 7 is rotated at a relatively slow speed in clockwise direction, so that the knives will be pulled in a circular path around the inner surface of the still. This pulling operation is more effective than a pushing operation, as the knives or blades are less liable to become jammed. As arranged, each of the blade-carrying levers acts with a yielding pressure, so that the blades can readily ride over irregularities in the still wall. At the same time, their cutting edges project outwardly in the direction of rotation so that they act to effectively scrape the carbon deposit from the wall.

The stuffing box 9 preferably consists of a lower packing 9^a and an upper packing 9^b, and an intervening metallic sleeve or spool 9^c, having a grooved periphery. Communi-

cating with the peripheral groove of this spool is an offtake pipe 9^a. The purpose of this arrangement is to catch and lead off any oil vapors which may escape from the still around the shaft, and thus prevent their reaching the top of the packing box where they might ignite. By this trap carrying off these vapors, the upper packing 9^b is free from pressure, and there will be no escape of vapor at the top of the box.

10 I do not wish to limit myself to the particular means herein shown and described for yieldingly pressing the scraper blades into action, as it is obvious that other means may be employed within the scope of my broader claims.

I claim:

20 1. In an oil-cracking still having a curved inner surface, a central shaft extending within the still, a plurality of arms fixed to said shaft, a lever pivoted to each of said arms and having a forwardly inclined scraper thereon adapted to be pulled along the inner surface of the still upon rotation of said central shaft, and a weight mounted to act upon each of said levers to press the scrapers against such inner surface, said weights being effective on said levers intermediate the pivotal mounting thereof and the scraper, substantially as described.

25 2. A still for cracking oil comprising a cylindrical upper portion and a bottom portion of inverted cone shape terminating in a discharge opening, a series of yieldingly mounted scrapers cooperating with the cylindrical upper portion for supplying scraped material to the bottom portion and a rigidly mounted scraper cooperating with substantially the entire surface of the cone shaped 30 lower portion, for advancing material to the discharge opening, substantially as described.

35 3. In a vertical oil-cracking still having a curved inner surface, a center shaft extending within the still, a plurality of arms fixed to said shaft, a scraper lever pivoted to each of said arms, and a weight mounted to act upon each of said levers to continuously press the scrapers against such inner surface, each 40 of said levers extending backwardly from the direction of their rotation and having their blades inclined forwardly in the direction of rotation, said blades being formed on the levers rearwardly of the pivotal mounting on the arm, substantially as described.

45 4. In apparatus for scraping stills, a rotatable shaft, a plurality of arms extending radially therefrom, a plurality of scrapers mounted loosely on the arms, weights operatively attached to the scrapers at a point intermediate the scraping edges and the scraper mountings whereby the scrapers are held 50 against the wall of the still.

5. In combination with a vertical still, a 55 rotatable shaft vertically mounted therein, a

plurality of arms extending radially from said shaft, scrapers loosely mounted on said arms, a lever operatively cooperating with each scraper at a point intermediate the scraping edges and the scraper mountings and weights in operative connection with the levers whereby the scrapers are held against the vertical wall of the still.

6. In combination with a vertical still, a rotatable shaft vertically mounted therein, a plurality of arms extending radially from said shaft, a plurality of scrapers loosely mounted on said arms, and weighted members arranged to exert force on the scrapers intermediate the scraper mountings and the scraper edges so as to hold said scrapers against the wall of the still.

In testimony whereof, I have hereunto set my hand.

L. B. CUDDY.
